UNITED STATES PATENT OFFICE.

THOMAS G. PLANT, OF BOSTON, MASSACHUSETTS, ASSIGNOR TO UNITED SHOE MACHINERY COMPANY, OF PATERSON, NEW JERSEY, A CORPORATION OF NEW JERSEY.

WORK-SUPPORT.

1,120,080.

Specification of Letters Patent.

Patented Dec. 8, 1914.

Continuation of application Serial No. 373,276, filed May 13, 1907. Renewed April 12, 1910, Serial No. 554,963. This application filed April 13, 1910. Serial No. 555,295.

To all whom it may concern:

Be it known that I, THOMAS G. PLANT, a citizen of the United States, residing at Boston, in the county of Suffolk and State of 5 Massachusetts, have invented an Improvement in Work-Supports, of which the following description, in connection with the accompanying drawings, is a specification like letters on the drawings representing like 10 parts.

The invention herein described relates to shoe supports, and more particularly to supports for sustaining a shoe in position while the heel is being treated, although, as will 15 be understood by those skilled in the art, it may be employed for other purposes.

The aims and purposes of the present invention are to provide a shoe support of the general type mentioned, which shall be simple 20 in construction and efficient for properly sustaining the shoe in position for treatment, all of which and other objects will best be made clear from the following description and accompanying drawings of

25 one form or embodiment of means for carrying the invention into practical effect, it being understood that the invention is not circumscribed by the illustrated details, but is defined in its true scope by the claims.

30 The shoe support herein is of the laterally expandible type to be employed in connection with shoes which are treated while not mounted on the usual wooden last, and means are herein provided for causing such 35 lateral expansion of the shoe support or jack as the shoe is moved to operative position with respect to the means for treating it, all as clearly pointed out in my prior application, Ser. No. 373,276, filed May 13, 1907,

40 now Patent No. 958,306, to which reference may be had for a detailed description of means, such as heel breasting means, for acting on the heel of a shoe sustained by the shoe support, which forms the subject of 45 the present application.

In the drawings:—Figure 1 is a side elevation showing sufficient of a heel breasting machine to make clear the relation of the present invention thereto and its construction; Fig. 2 is an enlarged detail detached view looking from the left at the lower part of Fig. 1; Fig. 3 is a sectional view on the line 3—3 of Fig. 2; Fig. 4 is an enlarged side view of the upper part of the shoe sup-

port, some of the parts being broken away; 55 Fig. 5 is a view of the parts shown in Fig. 4, looking from the right; Fig. 6 is a sectional view taken on the line 6—6 of Fig. 4; and Fig. 7 is a top or plan view of the jack plate to be described. 60

The machine frame for supporting the operating parts of the machine may be of any usual or desired character, and herein is represented as a column 1 which may be of any form and kind suitable to the purpose 65 intended. The lower portion of the column 1 is preferably provided with a lug or bracket 2 to which is fixed a pin 3, as by means of a set screw 4, and pivotally mounted on said pin 3 is the jack standard 5 which 70 extends upward from its pivotal mounting through a guide plate 6 which is movable longitudinally of the bracket or table 7. The jack standard is provided with a stop 8 adapted to engage a yielding bunter 9 as the 75 jack standard is moved to the left, Fig. 1, to carry the shoe into operative position, as will hereinafter more fully appear.

At its upper portion, the jack standard 5 is provided with a socket or recess 10, Figs. 80 4, 5 and 6, which may, if desired, be formed in the enlarged portion 11 at the upper part of the standard. This enlarged portion 11 is provided with guiding surfaces 12 adapted to slide between the guide portions 13 of 85 the bracket or table 7, as clearly indicated in Fig. 6.

Extending into the socket 10 at the upper end of the jack standard is the jack post 14 which may, if desired, be provided with a 90 shoulder 15 to rest upon the top extremity of the jack standard. The jack post 14 is conveniently retained in operative relation with the jack standard by means of a set screw 16, Figs. 4 and 5, the end of which, 95 17, enters a suitable recess in the jack post. As a further means of insuring the proper coöperative relation between the jack standard and jack post, a binding screw 18 extends through the upper portion of the jack 100 standard 5 and engages a suitable recess in the jack post, as clearly indicated in Figs. 4, 5 and 6, and while such set screws furnish a convenient means for securing the jack standard and jack post in proper relation, obviously other means may be employed.

The jack post 14 at its upper portion is

preferably expanded or enlarged, as at 19, and has the supporting brackets 20 for a pin 21 on which the laterally expansible jack members 22 and 23 may be supported for lateral swinging movement, as will presently appear. Each of the laterally expansible jack members 22 and 23 is provided with a depending tail piece or toe 24 and 25, respectively, said toes being connected by a spring 26, Fig. 5, whereby said toes 24 and 25 are normally drawn toward each other with a corresponding tendency to bring together or close the upper portions 22 and 23 of said laterally expansible jack members, somewhat in the manner of a pair of scissors, the construction being such that when the laterally expansible jack members and their respective toes are not under the influence of any other disturbing force, the spring 26 will act to hold said jack members and toes in the relative positions indicated by Figs. 5 and 6, with the upper ends of the jack members in closed relation.

Extending longitudinally through the jack post 14 is a jack expander 27, the lower end of which carries a collar 28, between which and the lower end of the jack post is interposed a spring 29, Figs. 4, 5 and 6, the construction being such that the jack expander 27 is normally held in lowered position by the spring 29. At its upper portion the jack expander carries a pin 30 on which is mounted a roll 31 adapted, on upward movement of the jack expander 27, to pass between the toes 24 and 25 of the expansible jack members and to separate the upper portions of said jack members. As a means for causing this upward movement of the jack expander and effecting such movement as the shoe is moved into operative position, as will hereinafter more fully appear, the present invention provides an expander actuator 32, Figs. 1, 2 and 3, the lower end of which is connected at 33 to a fixed collar 34 secured to the fixed pin 3. This fixed relation of the collar 34 and pin 3 may be secured in any suitable manner, but, as represented in Figs. 1 and 3, the collar is formed with the split lugs 35 and 36 which are connected by the binding screw 37, the construction being such that upon manipulation of the binding screw 37 the collar 34 may be fixed to the pin 3, as will be clearly understood by those skilled in the art.

The expander actuator 32 extends upward and is provided at its upper end with a seat 38 for the lower end of a spring 39 which is interposed between said seat and the lower end 40 of the jack expander, the construction being such that upon movement of the jack standard from the position shown in Fig. 1 to a position farther to the left in order to carry the shoe into operative position, a differential longitudinal

movement will result between the jack standard 5 and the expander actuator 32, with the result that the spring 39 will transmit an upward force to the lower end of the jack expander to thereby raise the same 70 against the tension of its depressing spring 29 and perforce cause the roller 31 at the upper end of the jack expander to separate the toes 24 and 25 and the jack members 22 and 23 connected thereto. The relation between the springs 29 and 39 is such that when the spring 39 is compressed by the relative upward movement of the expander actuator 32 as the jack standard moves to the left, the tension of the spring 29 will be 80 yieldingly overcome, and thus the laterally expansible jack members will be yieldingly separated. This yielding separation of the jack members is of importance in order to permit the jack head, as will presently be 85 described, to properly accommodate itself to the interior form and dimensions of the shoe, said springs 29 and 39 acting yieldingly to this end, the difference between their yielding force in opposite directions 90 being the yielding expansible force exerted upon the laterally expansible jack members.

Each of the laterally expansible jack members 22 and 23 carries a hinged jack head, the two portions of which form the completed jack head. In the present form of the invention each member has hinged to it, as at 41, Figs. 1 and 4, the head member 42, the under surface of one of which rests upon a plunger 43 normally pressed upward by a spring 44 seated in one of the jack members, as clearly shown in Figs. 4, 5 and 6. The upward action of the plunger or pin 43 is limited by the knuckle or knife joint 45, the surfaces of which come together in a well understood manner and limit the upward turning movement of the head members about their pivotal mountings. The pivotal mountings 41 of the head members are preferably located so that, when the jack standard has moved the shoe into operative position with respect to the breasting means, the tools which act upon the shoe will exert their force downward in a plane passing either through such pivotal mountings or to the left thereof, Figs. 1 and 4.

Each of the head members 42 is provided in its upper surface with a series of holes 46, any one of which is adapted to receive a pin 47 projecting from the under surface of a jack plate 48, Fig. 4, one of said jack plates being provided for each jack head member 42, and the upper surface thereof being preferably roughened to form a convenient character of sustaining means for the interior of the shoe. By means of the series of holes 46, as hereinbefore described, the jack plates 48 may be adjusted longitudinally in either direction upon their respective jack head members to accommodate to the interior for- 130

mation and contour of the shoe. In order that said jack plates shall not swing laterally when the pins 47 are adjusted in any one of the series of holes, the jack head members are each provided with a longitudinal slot 49, Fig. 4, into which projects a pin 50, extending from the lower surface of each of the jack plates 48, the construction being such that upon proper adjustment of the jack plates they will conform to the interior contour of the shoe and afford a proper supporting surface therefor, as will be readily understood. Inasmuch as the jack head members, each of which is pivotally mounted to its laterally expansible jack member, are separated more or less when the jack expander moves, as hereinbefore indicated, a guide pin 51 is secured to one of the head members 42, its other end projecting into a recess 52 in the companion head member, the construction being such that while the head members may separate by the lateral expansion of the jack members, in a manner hereinbefore described, the pin 51 will serve to guide said head members relative to each other and maintain them in proper lateral alignment.

The jack post 14 is preferably provided with a rearwardly extending bracket 53, on the top portion of which are a series of teeth 54 which are adapted to be engaged by a locking device 55 supported in a bracket 56 projecting from the machine frame, the construction being such that when the jack standard and jack have been moved into operative position to place the shoe in operative relation with the machine tools, the lock 55 will engage with the teeth 54 and maintain the parts in their proper position during the operation of the tools.

It has not been deemed herein necessary to show and describe the heel breasting means and their manner of acting upon the heel of the shoe, since this means is clearly set forth in the prior patent heretofore mentioned.

Obviously changes may be made in the details of construction and the parts illustrated whereby the present invention may be carried into practical effect, and it is to be understood that the invention is not circumscribed by such details except as herein-after pointed out by the claims.

While the term "jack" has been herein employed in describing the various parts, such as the laterally expansible jack members, the head, jack plates, and so on, it is to be understood that such term is not one of limitation but is used merely as identifying the parts described and as broadly inclusive of any sustaining means or the parts thereof for sustaining a shoe for the action of the operating tools.

What is claimed is:

1. In a shoe support, the combination of a pivotally mounted standard, laterally ex-

pansible jack members carried by said standard and movable laterally with relation to each other, each of said jack members carrying a tilting head member, and means for expanding the jack members as the standard is moved on its pivot. 70

2. In a shoe support, the combination of a pivotally mounted standard, laterally expansible jack members carried by said standard and movable laterally with relation to each other, each of said expansible jack members carrying a tilting head member, and means for so moving said jack members. 75

3. In a device of the character described, the combination of an expansible jack comprising two jack members movable laterally with respect to each other, a tilting head member carried by each jack member, means for yieldingly maintaining the head members in tilted position, and means for expanding the jack members. 80

4. In a device of the character described, the combination of a jack comprising two laterally movable jack members, a tilting head member mounted on each jack member, means to maintain the tilting head members in the same tilted relation with the jack members, and means to relatively move the jack members laterally. 90

5. In a shoe support, the combination of a standard, a laterally expansible jack supported by said standard, said expansible jack having a head portion constructed and arranged to tilt in a plane extending longitudinally of and at right angles to the bottom of the shoe supported thereon, and means for laterally expanding the jack. 100

6. In a shoe support, the combination of a jack support movable in a direction longitudinally of the shoe, a jack carried by said support and having a laterally expansible head to engage the interior of a shoe, said head being tiltable in a plane extending longitudinally of the shoe, and means for expanding said head laterally as the jack is moved to position the shoe. 105

7. A shoe support for sustaining a shoe for the action of a tool, comprising a two part jack, means for laterally separating the jack members to expand the jack, and a head mounted on the jack to tilt in a plane longitudinally of and substantially at right angles to the bottom of a shoe mounted thereon. 115

8. In a shoe support, a movable jack standard, laterally expansible jack members carried by said standard, each of said jack members carrying a tilting head member, and means for laterally expanding the jack members and head members as the standard is moved to carry the shoe to operative position. 120

9. In a shoe support, a movable jack standard, pivotally mounted jack members 130

carried thereby, longitudinally tilting head members carried by the jack members, and means for turning the jack members relatively on said pivotal mounting to separate 5 the jack members as the jack standard is moved.

10. In a device of the character described, the combination of a jack support, a jack mounted thereon and comprising laterally 10 expansible jack members, a tilting head member mounted on each jack member, a jack plate surmounting each tilting head member, and means for expanding and contracting the jack.

15. 11. In a device of the character described, the combination of an expansible jack, comprising pivotally mounted laterally movable jack members each having a tilting head member pivoted thereto, means for yieldingly holding the head members in tilted position, and means for relatively moving the jack members laterally to expand and contract the jack.

20. 12. In a device of the character described, the combination of an expansible jack, comprising laterally movable jack members each having a tilting head member pivoted thereto, an adjustable jack plate carried by said head members, means for yieldingly holding 30 the head members in tilted position, and means for relatively moving the jack members laterally to expand and contract the jack.

25. 13. In a laterally expansible jack, the combination of two jack members movable laterally with relation to each other, a tilting head member carried by each jack member, a jack plate surmounting each tilting head member, and means permitting adjustment of the jack plates on said head members.

30. 14. A shoe support, comprising a jack, means for sustaining said jack for movement to and from operative position, said jack comprising two jack members movable laterally with relation to each other, and means for automatically moving the jack members laterally as the jack sustaining means is moved.

35. 15. In a shoe support, the combination of jack sustaining means, a laterally expansible jack having longitudinally tilting head members to engage the interior of a shoe,

and means for expanding the jack laterally as the jack is moved to position the shoe. 55

16. In a shoe support, a movable jack standard, jack members carried thereby and mounted for relative lateral movement, a jack expander, and means acting through the jack expander as the jack is moved to 60 position the shoe for the action of a tool to yieldingly separate the jack members.

17. In a shoe support, a standard, a jack mounted thereon and comprising members pivoted to the standard, each of said members having a head portion and a projection, and means movable between the projection as the standard is moved to expand the head portions. 65

18. In a shoe support, the combination of laterally expansible jack members each carrying an adjustable plate for engaging the interior of a shoe, each of said members having projecting portions, and means acting on said projecting portions to expand 75 the jack members laterally.

19. In a shoe support, the combination of laterally expansible jack members for engaging the interior of a shoe, each of said members having projecting portions, and means acting on said projecting portions to expand the jack members laterally, and a spring acting on said projecting portions to contract the jack members. 80

20. In a shoe support, the combination of 85 a movable jack standard, jack members carried thereby and mounted for lateral separation to conform to the interior of a shoe, and means acting longitudinally of the jack standard as it is moved to laterally separate 90 the jack members.

21. In a shoe support, a pivotally mounted standard, a jack carried by said standard and comprising two jack members pivotally supported on said standard and each carrying a head portion to engage the interior of a shoe, and means having a part movable longitudinally of the standard to separate the head portions. 95

In testimony whereof, I have signed my 100 name to this specification, in the presence of two subscribing witnesses.

THOMAS G. PLANT.
